(57) **CLAIM**

The ornamental design for a pot and pan pull-out organizer, as shown and described.

DESCRIPTION

FIG. 1 is a top right perspective view of a pot and pan pull-out organizer in a collapsed configuration showing our new design;

FIG. 2 is a top left perspective view thereof;

FIG. 3 is a bottom left perspective view thereof;

FIG. 4 is a front view thereof;

FIG. 5 is a back view thereof;

FIG. 6 is a top view thereof;

FIG. 7 is a bottom view thereof;

FIG. 8 is a left view thereof;

FIG. 9 is a right view thereof;

FIG. 10 is a top right perspective view of a pot and pan pull-out organizer in an extended configuration;

FIG. 11 is a top perspective view thereof;

FIG. 12 is a detail perspective view of a pot and pan pull-out organizer in a collapsed configuration taken with reference to circle 12 of FIG. 1;

FIG. 13 is a detail perspective view taken about circle 13 of FIG. 1;

FIG. 14 is a detail perspective view taken about circle 14 of FIG. 2;

FIG. 15 is a detail perspective view taken about circle 15 of FIG. 2;

FIG. 16 is a detail perspective view taken about circle 16 of FIG. 3;

FIG. 17 is a detail perspective view taken about circle 17 of FIG. 4;

FIG. 18 is a detail perspective view taken about circle 18 of FIG. 5;

FIG. 19 is a detail perspective view taken about circle 19 of FIG. 6;

FIG. 20 is a detail perspective view taken about circle 20 of FIG. 7;

FIG. 21 is a detail perspective view taken about circle 21 of FIG. 10;

FIG. 22 is a detail perspective view taken about circle 22 of FIG. 10; and,

FIG. 23 is a detail perspective view taken about circle 23 of FIG. 11.

The broken line showing of the bracket mounting holes in FIGS. 12-23, the broken line showing of a hook in FIGS. 1-5, 7-10, 12, 14, 16-18, 20, and 22, and the broken line showing of the internal rail in FIGS. 1, 2, 4-7, 10, 11, 17, 18, 21, and 23, is included for the purpose of showing environmental structure and forms no part of the claimed design.

1 Claim, 23 Drawing Sheets

Related U.S. Application Data

which is a continuation of application No. 29/541, 860, filed on Oct. 8, 2015, now Pat. No. Des. 781,670.
